UNITED STATES PATENT OFFICE.

JAMES H. CAFFREY, OF BEAVER FALLS, PENNSYLVANIA, ASSIGNOR TO ASBESTOS PROTECTED METAL COMPANY, OF BEAVER FALLS, PENNSYLVANIA, A CORPORATION OF MASSACHUSETTS.

APPARATUS FOR FORMING PROTECTED METAL SHEETS.

1,212,324.

Specification of Letters Patent. Patented Jan. 16, 1917.

Application filed October 14, 1914. Serial No. 866,685.

To all whom it may concern:

Be it known that I, JAMES H. CAFFREY, a citizen of the United States, residing in Beaver Falls, in the county of Beaver and 5 State of Pennsylvania, have invented an Improvement in Apparatus for Forming Protected Metal Sheets, of which the following description, in connection with the accompanying drawings, is a specification, like 10 characters on the drawings representing like parts.

This invention relates to an apparatus for forming protected metal sheets, of that character in which the side edges of the metal 15 sheet are enveloped by the protective layer.

The apparatus is especially adapted for forming asbestos protected metal sheets, comprising an iron or steel sheet covered with an adhesive, such as asphalt or bitumen, and an outer layer of asbestos in sheet 20 form.

In the present instance, the apparatus is represented as employed for forming protected metal sheets of substantially small 25 size, substantially that of a shingle, and to facilitate description, the product formed by the apparatus will be hereinafter referred to as a protected metal shingle.

The apparatus herein shown comprises 30 essentially a feed member, a coating member and a covering member. The feed member feeds the metal blank or shingle into the coating member, which is provided with a bath of asphalt or other adhesive through 35 which the metal shingle is fed, and from which it passes to the covering member, in which the coated metal shingle is covered by a sheet, layer or web of asbestos paper or other fibrous material, which is arranged 40 with relation to the metal shingle so that its sides may be folded over the side edges of the shingle and upon the upper surface of the same. Provision is made for distributing the coating material or asphalt 45 over the upper and lower surfaces of the metal shingle, and for insuring a surplus of asphalt at or near the transverse center of the metal shingle, to provide for sealing the overlapping edges of the protective 50 layer or sheet, as will be described. Provision is also made for sealing together the overlapping edges of the protective layer or sheet, as will be described.

These and other features of this invention

will be pointed out in the claims at the end 55 of this specification.

Figure 1 is a side elevation of an apparatus embodying this invention. Figs. 2 and 3 are plan views of the apparatus shown in Fig. 1 when read together. Figs. 4 and 5, 60 details of one of the distributing or spreading rolls shown in Fig. 1. Fig. 6, an enlarged section, taken on the line 6—6, Fig. 3, and Fig. 7, an enlarged section taken on the line 7—7, Fig. 1. 65

In the present instance I have shown one construction of apparatus in which the metal shingles *a* are fed automatically by a feed member *b* into a coating member *c*, in which the metal shingle is provided with 70 a coating of liquid asphalt or other adhesive material, and from which the coated metal shingle *a* is fed to a covering member *d*, by means of which the coated metal shingle is hermetically sealed by a protective sheet or 75 layer *e*. In the present instance, the feed member *b* is shown as an endless carrier or link chain 10, which is passed about sprocket wheels 12, 13, mounted upon shafts 14, 15, 80 suitably supported and located at the opposite ends of a guideway, formed by side bars 16, 17, see Figs. 3 and 7, which are supported by a framework 18.

The link chain 10 is moved in a substantially horizontal plane between the side bars 85 16, 17, and is provided at suitable intervals with lugs or projectives 19, which serve as pushers for the metal shingle *a*, to push the same forward into engagement with a pair of feed rolls 20, 21, mounted in boxes 22, 23, 90 the upper feed roll 20 being permitted to yield with relation to the lower feed roll 21 by springs 24 in a manner well understood.

The metal shingle *a* is fed by the feed rolls 20, 21, under a guide or deflecting roll 95 25, which deflects the metal shingle down into guideways 26, 27, formed by guide bars 28, 29, which extend lengthwise of a kettle or vat 30 containing adhesive material, preferably asphalt or like bitumen. The kettle 100 30 may be heated in any suitable manner to keep the asphalt fluid. The guide bars 28, 29, are curved, so that the metal shingle *a* on its passage through the coating bath contained in the kettle or vat 30, will be submerged in the coating bath or asphalt, so as to be entirely covered by the same. The metal shingle *a* is fed through the coating 105

apparatus, as shown, by a plurality of pairs of feed rolls 31, 32, which are mounted on shafts 33, 34, journaled in boxes 35, 36, the upper roll 31 of each pair of feed rolls being 5 yieldingly backed up by springs 37, so that the rolls 31 may move toward and away from the rolls 32 to compensate for different thicknesses in the shingles α and to impart the proper bite by the rolls 31, 32, upon the shingles. The pairs of feed rolls 31, 32, are 10 separated from one another by spaces, which are less than the length of the metal shingles.

At the delivery end of the kettle or vat 30, provision is made for spreading the asphalt 15 or other coating material evenly over the greater portion of the metal shingle; and for providing for a surplus of asphalt at or near the transverse center of the metal shingle. For this purpose a pair of rolls 40, 41 are 20 mounted upon shafts 42, 43, with the upper shaft 42 journaled in boxes 44, which are yielding backed up by springs 45. The rolls 42, 43, are provided on their circumference with helical grooves or channels 46, 47, see 25 Figs. 1 and 4, which extend from, at or near the center of the rolls toward their opposite ends, and said rolls are also provided with substantially parallel longitudinally extended grooves or channel 48, which intersect the 30 helical grooves. These grooves serve to distribute the asphalt evenly over the shingle from, at or near the side edges thereof, to the transverse center thereof. The upper roll 40 may and preferably will be provided 35 substantially at or near its longitudinal center with an annular groove 49, which serves as a reservoir to hold a surplus quantity of asphalt, for a purpose as will be described.

40 The rolls 40, 41, also act as feed rolls to feed the coated metal shingle onto the web, sheet or layer e of protective fibrous material, preferably asbestos paper, which is taken from a roll 51 and led over a support 45 or bed roll 52, which is located near the delivery end of the kettle 30. The protective layer or sheet e is then fed through the covering apparatus, which may and preferably will be made as herein shown, and which is 50 provided with a pair of feed rolls 53, 54, located adjacent to the bed roll 52 and supported upon a suitable framework 55. A second pair of feed rolls 58, 59, is located at the opposite end of the framework 55, and 55 between these pairs of feed rolls is located a series of supporting rolls 60 herein shown as three in number, and also a plurality of pairs of folding over rolls 61. The covering apparatus is further provided with means 60 for turning the portions of the covering sheet e which projects beyond the sides of the metal shingle, first into a position substantially at right angles to the metal shingle and then over upon and substantially 65 parallel with said shingle.

In the present instance, the bed roll 52 has coöperating with it upright side pieces 62, 63, which converge toward the feed rolls 53, 54, and serve to bend the sides of the covering sheet e into a substantially upright position and to direct said sides between end flanges on the feed rolls 53, 54, from which the up-turned sides of the paper sheet are carried forward to the first pair of folding over rolls 61, by which the sides of the paper sheet are partially folded over the shingles. The partially folded sides of the sheet are then folded over still farther toward the longitudinal center of the metal shingle by the second pair of folding over rolls 61, and the folding is completed by the third set of folding over rolls 61 as represented in Fig. 2. It will be understood, that the pairs of folding over rolls 61 are properly shaped and proportioned to gradually turn or bend 85 the sides of the paper sheet and thus avoid cracking or breaking the same. The last set or pair of folding over rolls 61 brings the folded over sides of the paper sheet into superimposed position substantially parallel 90 with the metal shingle, see Fig. 2, and the over-lapping sides of the paper sheet are pressed together by passing through the pressure rolls 58, 59, from which they pass between a pair of rolls 75, 76, the lower one 95 of which has passed about it an endless band or conveyer 77, by which the covered shingle is carried away from the apparatus.

The upper roll 75 is a presser and feed roll, which is preferably provided with a 100 covering of felt 79, which serves to press the overlapping side of the paper sheet marked 80 in Fig. 2 down into contact with the coated surface of the metal shingle at the edge of the underlying side of the paper 105 sheet marked 81, and the felt covering also presses the protective sheet into close contact with the metal sheet or shingle and compensates for irregularities in the surface of the shingle. The flap 80 of the paper 110 sheet, which overlaps the other flap 81 of the paper, is cemented to the latter by the surplus cement or asphalt, which is supplied to the upper surface of the metal shingle by the annular groove or channel 49, which latter insures a sufficient supply of asphalt or cement for this purpose.

By reference to Fig. 2, it will be seen that the sheet or web e of asbestos or other paper has its sides folded over a plurality of 120 metal shingles α , which are spaced apart, and that between adjacent metal shingles the sides of the paper sheet are cemented to the lower layer of the said paper sheet, with the result that each coated shingle is sealed 125 at its sides and ends.

In the present instance the metal sheet is described as a metal shingle and is shown as of a size approximately that of the ordinary shingle, but it is not desired to limit the in- 130

vention to an apparatus for covering metal shingles, as it is evident that it can be proportioned and arranged to handle metal sheets of any desired size within limits. 5 The rotatable members of the feeding and coating members may be operatively connected through suitable gears 90 with a main or driving shaft 91, and as this method of driving is well known, it is not deemed necessary to identify by number the individual gears.

The operation of the apparatus may be briefly described as follows: Assume that the kettle 30 is heated and the asphalt bath 15 contained therein is fluid. The operator starts the main or driving shaft 91 in motion, which through the gears 90 or otherwise, sets the feed mechanisms in motion. He then places the shingles *a* upon the link 20 chain 10 between the lugs 19, and each shingle is delivered to the feed rolls 20, 21, which feed it under the roll 25, by which it is deflected down into the guide ways 26, 27, in the kettle 30, and is fed forward into 25 and out of the bath of the fluid asphalt by the rolls 31, 32. The metal shingle coated with asphalt is then passed between the rolls 40, 41, which spread the asphalt evenly over the shingle except at the center of the 30 upper surface of the shingle, which receives a surplus from the groove 49. The spreading rolls 40, 41 feed the coated shingle onto the web or sheet *e*, as the latter is drawn over the bed roll 52, and thereafter 35 the coated metal shingle *a* rests upon the sheet *e* and is carried forward thereby between the flanges on the roll 53 and the body of the roll 54, and has its upper surface 40 covered by the side portions of the sheet *e* being folded over and pressed down upon the coated upper surface of the shingle as above described.

I have herein shown and described one construction of apparatus embodying this 45 invention, but it is not desired to limit the invention to the particular construction shown.

The helical grooves in the rolls 40, 41, serve to carry the surplus asphalt away 50 from the side edges of the rolls and toward the transverse center of the same and into the annular groove 49, wherein it is retained to provide a surplus for cementing the overlapped portions 80, 81, of the paper layer.

55 Claims:

1. In an apparatus of the character described, in combination, a kettle for containing a bath of adhesive material, means for feeding a metal sheet into and out of said 60 kettle to coat the same with adhesive material, means for applying to one surface of

the coated metal sheet a layer of fibrous material of greater width than said metal sheet to leave portions of the said fibrous layer projecting beyond the sides of the 65 metal sheet, and means for folding the projecting side portions of the fibrous layer over upon the other surface of the coated metal sheet, substantially as described.

2. In an apparatus of the character described, in combination, a kettle for containing a bath of adhesive material, means for feeding a metal sheet through said kettle to coat the same with adhesive material, means for applying to one surface of the 75 coated metal sheet a layer of fibrous material of greater width than said metal sheet to leave portions of the said fibrous layer projecting beyond the sides of the metal sheet, and means for folding the projecting 80 side portions of the fibrous layer over upon the other surface of the coated metal sheet.

3. In an apparatus of the character described, in combination, a kettle for containing a bath of adhesive material, means for 85 feeding a metal sheet into and out of said kettle to coat the same with adhesive material, means for spreading the adhesive material evenly over the surfaces of said metal sheet, means for applying to one surface of 90 the coated metal sheet a layer of fibrous material of greater width than said metal sheet to leave portions of the said fibrous layer projecting beyond the sides of the metal sheet, and means for folding the projecting 95 side portions of the fibrous layer over upon the other surface of the coated metal sheet.

4. In an apparatus of the character described, in combination, a kettle for containing a bath of adhesive material, means for feeding a metal sheet through said kettle to coat the same with adhesive material, means for applying a surplus of adhesive 100 material to one surface of the metal sheet 105 between the sides of the latter, means for applying to one surface of the coated metal sheet a layer of fibrous material of greater width than said metal sheet to leave portions of the said fibrous layer projecting 110 beyond the sides of the metal sheet, and means for folding the projecting side portions of the fibrous layer over upon the other surface of the coated metal sheet.

In testimony whereof, I have signed my 115 name to this specification in the presence of two subscribing witnesses.

JAMES H. CAFFREY.
